[57] **CLAIM**

The ornamental design for a collapsible carton with retractable, foldable handle, as shown and described.

DESCRIPTION

FIG. 1 is a perspective view of a collapsible carton with retractable, foldable handle showing my new design;

FIG. 2 is a bottom plan view thereof;

FIG. 3 is a front elevational view thereof; the rear elevational view being a mirror image thereof;

FIG. 4 is a top plan view thereof;

FIG. 5 is a right side elevational view thereof; the left side elevational view being a mirror image thereof;

FIG. 6 is a perspective view thereof with a retractable handle in an extracted position;

FIG. 7 is a perspective view thereof with a retractable handle in an extracted position and folded; and,

FIG. 8 is a perspective view thereof similar to as shown in FIG. 7 but handle folded in an alternate position.

FIG. 1

FIG. 2

FIG. 3

FIG. 5

FIG. 4

FIG. 6

FIG. 7

FIG. 8
